UNITED STATES PATENT OFFICE.

JULIUS KAHN, OF JERSEY CITY, NEW JERSEY, ASSIGNOR TO PACIFIC NOVELTY COMPANY, OF NEW YORK, N. Y., A CORPORATION OF NEW YORK.

CLASP.

1,221,996.

Specification of Letters Patent. Patented Apr. 10, 1917.

Application filed October 16, 1916. Serial No. 125,863.

To all whom it may concern:

Be it known that I, JULIUS KAHN, a citizen of the United States, and a resident of Jersey City, county of Essex, and State of New Jersey, have invented a certain new and useful Improvement in Clasps, of which the following is a specification.

The invention relates particularly to a device used as a hair ornament and known as a "braid clasp" although it may be made and used in various ways such as for a lingerie clasp and the like.

The primary object of this invention is to provide an article of this character which is of simple and economical construction and which involves a minimum of parts and material with considerable ease in assemblage.

With this object in view, I have devised the construction shown in the accompanying drawing forming part hereof and more particularly pointed out in the specification and claim hereto attached.

Reference is to be had to the accompanying drawing, in which—

Figure 1 is a side elevation of my improved clasp in closed position;

Fig. 2 is a plan view of the same;

Fig. 3 is a sectional view on the line 3—3 of Fig. 1, looking in the direction of the arrows; and

Fig. 4 is a sectional view on the line 4—4 of Fig. 1, looking in the direction of the arrows.

Throughout the various drawings, similar reference characters designate similar parts.

In the preferred embodiment of my invention, as shown in the accompanying drawing, the entire device is made from a single flat strip of resilient material, which comprises an upwardly arched member 1

which is curled or bent at each of its ends as at 2 and 3.

Extending from the semi-circular bend 2 is the locking tongue 5, which is twisted, as at 4, so that its flat sides are vertically disposed, or at right angles to the flat surfaces of the member 1. The upper edge of this locking tongue is provided with a hump 6, the edge of the hump being provided with a plurality of teeth or serrations 7 to engage the hair and hold the device in place.

To lock in tongue 5 and retain the device in its closed position, as shown in Fig. 1, the end 8 of the bend or loop 3 is provided in its upper edge with a recess 9 into which the tongue 5 fits, as shown in Fig. 4, said tongue being held therein by the resiliency of the material.

To open the device the tongue 5 is merely moved clear of the recess and the tongue pushed sidewise and downwardly until it assumes the position shown in dotted lines in Fig. 1.

From the foregoing, it is obvious that my invention is not to be restricted to the embodiment herein shown but is broad enough to cover all structures coming within the scope of the annexed claim.

What I claim is:

A clasp having a flat member, said member being bent upon itself at one end to form a loop, a recess formed in the upper edge of said loop, the flat member being bent upon itself at its other end to form a locking tongue for engagement with the recess, said tongue being twisted so that its flat sides are vertical, a hump formed on the upper edge of said tongue and a plurality of teeth formed in said hump.

Signed at the city, county and State of New York, this 13th day of October, 1916.

JULIUS KAHN.
